ABSTRACT

An apparatus for electroslag remelting of high-quality metal in which a mechanism for feeding electrodes into a mold is mounted directly on the side walls of the mold so that the apparatus is considerably simplified, particularly in the height dimensions thereof. The apparatus is most suitable for casting large ingots, for example, of a weight to 3 tons and higher.

APPARATUS FOR ELECTROSLAG REMELTING OF METALS AND ALLOYS

This is a continuation of application Ser. No. 42,911, filed June 3, 1970, now abandoned.

BACKGROUND OF THE INVENTION

The present invention relates to equipment for making high-quality metal and, more specifically, the invention relates to apparatus for electroslag remelting of metals and alloys.

PRIOR ART

Well known in the art are apparatus for electroslag remelting comprising a pan with a cooled mold mounted thereon, a mechanism for feeding consumable electrodes into the mold and a device for bottom gate charging of slag (cf. the Belgium Patent No. 689,297 with priority of Jan. 13, 1967).

In the above-said apparatus, the mechanism for feeding consumable electrodes into a mold consists of a single column, portal or four-column structure, which is mounted directly on a foundation or on a supporting frame having a movable carriage or a cross-piece with a drive provided with a screw or chain transmission.

Such mechanisms have a considerable height, are complex and bulky due to the presence of auxiliary metal structures and, therefore, must be located in special buildings having an adequate height, which fact considerably increases the building cost of workshops for electroslag remelting.

An object of the present invention is to eliminate the above-mentioned disadvantages.

SUMMARY OF THE INVENTION

The specific object of the invention is to provide an apparatus for electroslag remelting of metals and alloys with a simple and compact mechanism for feeding the consumable electrodes having much a lesser height than the known mechanism for feeding the electrodes.

Generally, the invention relates to an apparatus for the electroslag remelting of metals and alloys including a cooled mold for casting an ingot therein, the mold having inner and outer side walls, an upper end and an open bottom end, a pan on which the open bottom end is mounted, a means for bottom gate pouring of slag into the mold, a mechanism for feeding consumable electrodes into the mold via the upper end thereof, and means mounting the feeding mechanism directly on the outer side wall of the mold, thereby considerably reducing the height of the apparatus and simplifying its construction.

The mechanism for feeding the electrodes is preferably mounted on brackets secured on the external side-walls of the mold.

It is also expedient to provide the apparatus with a device for side holding of the dummy bar on the pan.

The mechanism for feeding the electrodes may be provided with a hydraulic drive.

The apparatus according to the present invention allows the problem at hand to be successfully solved and can be most effectively used for producing large ingots, for example, weighing 3 tons and higher during the remelting of consumable electrodes having a cross section only slightly less than that of the internal space of

the mold in which these electrodes are being remelted (for example, with a ratio of the sectional area of the electrode to the internal space of the mold equal to or greater than 0.8). In this case, the travel of the electrode in the process of melting is limited to a very short distance, and therefore, the height of the mechanism for feeding the electrode and of the entire apparatus is small.

The above and other objects and features of the invention will appear more fully hereinafter from a consideration of the following description taken in connection with accompanying drawing showing a general diagrammatic view partly in elevation and partly in cross section of the apparatus for electroslag remelting of metals and alloys.

DETAILED DESCRIPTION OF THE INVENTION

The apparatus comprises a pan 1 with a device 2 for bottom gate pouring of slag and with a device 3 for transversely securing a dummy bar 4. The dummy bar 4 is positioned in a recess 4a provided in the pan 1 and the device 3 includes a slide 3a movable horizontally in a recess 1b in the pan 1 for clamping the dummy bar and upper surface 3b of the slide is flush with upper surface 1' of the pan. Mounted on the pan 1 is a cooled mold 5. The mold is provided with spaced-apart inner and outer side walls 5a and 5b, an open upper end 5c and an open bottom end 5d. It will be noted that brackets 6 are secured on the outer wall 5b of the mold by suitable means. Mounted on the brackets is a mechanism 7 for feeding a consumable electrode 8 into the mold 5 through the upper end 5c. The feeding mechanism is a hydraulic mechanism including a cylinder 7a, a piston 7b and a piston rod 7c. The arrows indicate the coupling of the mechanism 7 with a hydraulic system. The brackets 6 are secured to the mold at a distance from the upper end 5c which is equal to the height of the cylinder 7a of the feeding mechanism 7. The electrode 8, under the action of its own weight through its top shoulder 9, is suspended from a supporting current-conducting ring 10 which, in turn, is secured on the piston rods of mechanism 7 and is electrically insulated therefrom by means of an insulating spacer 11. The voltage from a power source (shown by arrows in the drawing) is applied to the ring 10 and the upper portion of the mold 5. The mold is provided with devices in the form of trunnions 12 for lifting the mold by a workshop crane.

The apparatus operates as follows.

The mold 5 through the device 2 is filled with slag to a level at which the electric circuit is closed and, therefore, the process of electroslag remelting starts. As soon as the electrode 8 melts, it is fed downwardly by means of the mechanism 7. After building-up an ingot of a required height, the feeding of the electrode is stopped, with the remaining residue of the electrode being removed by the crane. The ingot is held in the mold 5 until solidification of the metal and slag, and thereafter, the mold 5 together with the mechanism 7 for feeding the electrode secured on the mold is removed from the ingot, the dummy bar 4 is released by the device 3, and the ingot is removed from the pan 1. Thereafter, the pan 1 and the device 2 are cleaned from the solid slag, a new dummy bar 4 is set in place and clamped, the mold 5 is again set on the pan 1, a new consumable electrode is supported on the current-

conducting ring 10, and the process of remelting is repeated.

The working stroke of the mechanism 7, for example for casting an ingot weighing 4200 kg, with a cross section of 600 × 600 and a height of 1500 mm, is only 230 mm. Such a stroke is easily provided by the hydraulic system of the electrode feed mechanism.

We claim:

1. An apparatus for the electroslag remelting of metals and alloys comprising in combination: a cooled mold for casting an ingot therein, said mold having side walls, an upper end and an open bottom end, a pan on which the open bottom end of the cooled mold is mounted, a means for bottom gate pouring of slag into the mold, a mechanism for feeding consumable electrodes into the mold via the upper end thereof, and means mounting the feeding mechanism directly on the side walls of the mold, said pan being provided with a recess, and a dummy bar positioned in the recess, and further comprising a means for transversely clamping the dummy bar in the pan, said clamping means including a slide movable horizontally in the recess in the pan and said slide having an upper surface flush with the upper surface of the pan.

2. An apparatus for the electroslag remelting of metals and alloys, comprising a cooled mold open at the top and bottom having an open top and bottom for casting an ingot therein, a pan for mounting the bottom of said mold, means for feeding consumable electrodes into the mold from the top, means for applying electric current to the top part of the electrode, said electric

current applying means being connected to said means for feeding the consumable electrodes, and means for retaining the electrode feeding means and current applying means directly on the walls of the mold during 5 ingot casting, said retaining means including means for enabling removal of the mold, the electrode feeding means, and the current applying means in unison from the ingot to permit removal of the ingot from the pan.

10 3. The apparatus for the electroslag remelting of metals and alloys as claimed in claim 2, in which the pan is provided with a slot open on top and ends in a central part of the pan, said slot accommodating a slide having a top surface coinciding with the pan surface and in contact with a bottom flange of the mold when the mold is mounted on the pan and adapted to move towards the center of the pan along the slot, and means for clamping a dummy bar between the end face of the 15 slide facing the center of the pan and the end face of the slot.

20 4. The apparatus for the electroslag remelting of metals and alloys as claimed in claim 2, in which the means for retaining the electrode feeding means and the current applying means includes a bracket secured on the wall of the mold, the feeding means including a cylinder, a piston mounted within the cylinder and a piston rod carried by the piston, with the bracket being fixed at a distance from the open top of the mold equal to the 25 height of the cylinder.
